MEANS FOR RETARDING RATE OF FIRING
OF AUTOMATIC FIREARMSGeorge Ironside, Hartford, Conn., assignor to
Colt's Patent Fire Arms Manufacturing Com-
pany, Hartford, Conn., a corporation of Con-
necticut

Application March 27, 1941, Serial No. 385,397

2 Claims. (Cl. 89—3)

My present invention relates to automatic firearms of the recoil type wherein the barrel of the firearm is supported within the breech casing for longitudinal reciprocating movement during functioning of the firearm.

Prior to my present invention, automatic firearms of the recoil belt-fed cartridge type have been designed and constructed to accomplish the utmost in rapidity of firing of the cartridges automatically fed into the firearm during functioning thereof by the recoil and counter-recoil movements of parts within the breech casing including the movement of the barrel extension and breech bolt. Also, certain moving parts within the breech casing at definite intervals are locked and unlocked by automatic operation effected by the firing of the cartridges and the relative recoil and counter-recoil movements of said parts. This has been effected by means of springs, and cams similar to those shown and described in Patent No. 1,293,021 and designated by the reference characters R, N, and I. Great rapidity of firing is desirable where the automatic firearms are mounted on aircraft. However, for ground use, under certain conditions, it is desirable to have the automatic firearm relatively slow in its action or functioning so that the rate of firing of the cartridges is materially reduced as compared with the very rapid firing of the firearms when used on aircraft.

In the firearm illustrated in said patent, an accelerator 0 is provided on the lock frame just behind the breech bolt when the breech is closed, and functions, as its name implies, to give an accelerated motion to the rearward movement of the breech bolt after firing of the cartridges, thus speeding up or increasing the rapidity of the automatic functioning of the firearm.

With the foregoing in mind, the general object of my present invention may be stated to reside in the provision of means for regulating the movement of parts of the breech mechanism which control the feeding of the cartridges into the chamber or breech end of the barrel and the firing thereof after the breech has been closed, and to control and especially reduce the rate of firing of the cartridges in an automatic firearm of the type above mentioned by eliminating acceleration of the breech bolt.

More specifically stated, the invention may be said to reside in the provision of means automatically operable during functioning of the gun to positively retard movement of the barrel and barrel extension into battery position subject to

movement of the breech bolt so that the barrel and barrel extension are not released for movement into battery position until the breech bolt has nearly completed its forward travel into 5 breech-closing position.

As will become hereinafter more apparent and will be pointed out in detail, the invention provides a special construction and relative arrangement of cooperating elements to effect the retarding of the feeding, charging, and firing mechanism of an automatic firearm whereby the rate or rapidity of firing is materially reduced as compared with the rate of firing under the construction and operation of said Patent No. 1,293,021 15 and other accelerated firearms designed especially to attain the utmost speed or rate of firing of a succession of cartridges automatically fed thereto.

In my present application I have disclosed two 20 mechanisms for effecting or accomplishing the foregoing objects and which may be used jointly or separately according to the rate of firing desired, that is, the invention contemplates and includes the provision of means provided on the 25 lock frame or similar device which limits and cushions rearward movement of the barrel extension to positively engage the barrel extension at a predetermined interval in its course of travel to prevent return of the barrel extension to battery position until said means is released by movement of the breech bolt close to breech-closing position. While this feature of the invention is 30 amply sufficient to materially reduce the rate of firing of an automatic firearm, such as shown and described in said Patent 1,293,021, I also provide means useable in connection with the retarding mechanism, generally mentioned previously herein, to further reduce the rate of firing and consisting generally in the provision of cushioning 35 or retarding means for the breech bolt and also preferably carried by the lock frame or similar device against which the barrel extension moves under the force created by explosion or firing of the cartridges. I, therefore, wish it to be understood that the present invention, as will become 40 hereinafter more apparent when the details of construction and operation of the parts are explained, covers constructions useable alternatively or jointly on a firearm, according to the 45 rate of firing desired.

In the accompanying drawings, I have shown the now preferred embodiment of the invention, but it will be understood that the drawings are intended for illustrative purposes only and are not 50 to be construed as defining or limiting the scope

of the invention, the claims forming a part of this specification being relied upon for that purpose.

In the drawings,

Fig. 1 is a side elevation of a breech casing and feed box, and parts mounted therein and connected therewith, of an automatic firearm of the recoil operated type with parts broken away and partly in section showing one feature of the invention;

Fig. 2 is a fragmentary view similar to Fig. 1 showing the breech bolt and barrel extension of the firearm in their rearmost recoil positions;

Fig. 3 is a view similar to Fig. 2 showing the barrel extension held against complete forward movement by mechanism forming a part of the present invention and just prior to release of said mechanism by counter-recoil movement of the breech bolt;

Fig. 4 is a top plan view of a barrel extension per se, such as shown in Figs. 1-3, inclusive;

Fig. 5 is a front end view on an enlarged scale of the barrel extension shown in Fig. 4;

Fig. 6 is an enlarged sectional view taken on the line and looking in the direction of the arrows 6-6 of Fig. 4;

Fig. 7 is a view similar to Fig. 6 looking in the direction of the arrows 7-7;

Fig. 8 is a fragmentary side view partly in elevation and partly in section showing a modification of the invention;

Fig. 9 is a view similar to Fig. 5 showing the modification of Fig. 8;

Fig. 10 is a view similar to Fig. 4 showing the cushioning and retarding mechanism of Fig. 4 in conjunction with additional cushioning and retarding mechanism for the breech bolt to further slow down the rate of firing;

Fig. 11 is a side elevation of the mechanism shown in Fig. 10 partly in section and with parts broken away and illustrating the breech bolt in its rearmost retarded position in dot-and-dash lines; and

Fig. 12 is a rear elevation of the cushioning and retarding mechanism with parts of Fig. 11 omitted.

Referring to the accompanying drawings and particularly to Figs. 1 and 2, the numeral 11 designates the breech casing of an automatic firearm suitably secured to a trunnion block 12 through which a barrel 13 is mounted and connected at its breech or rear end to a barrel extension 14 mounted within the breech casing 11 for longitudinal reciprocating movement therein. The numeral 15 designates the cover of a feed box mounted on top of the casing 11 and supporting a feed lever 16 which controls feeding of the cartridges successively into the gun, substantially as disclosed in said Patent No. 1,293,021.

The rear of the casing 11 is closed by a removable back plate 17 having handles 18 to be manually grasped when removing or applying the back plate for access to the interior of the casing and the mechanism contained therein. The back plate may be of any desired construction and secured to the casing by any suitable means so far as the present invention is concerned, but the one illustrated in the accompanying drawings is made substantially in accordance with the back plate illustrated in Patent No. 1,628,226 and includes as a part thereof a cushioning member 19 for the breech bolt 20 which is mounted in the casing for reciprocating movement above the barrel extension 14 and the lock frame or similar cushioning device 21 for the barrel extension 14,

and located at the rear of the casing immediately behind the barrel extension. The breech bolt is adapted to be moved rearwardly, by the force created by the firing of the cartridges, from the position of Fig. 1 to the position of Fig. 2 and to be returned from the position shown in Fig. 2 to the position shown in Fig. 1 by the spring 22, similar to spring 36 in said Patent No. 1,628,226 or the spring R in Patent No. 1,293,021 located between the back plate 17 and extending into the breech bolt connected therewith.

The cocking lever 23 and extractor 24 are operated by the reciprocating movements of the breech bolt, as disclosed in said foregoing patents.

As previously mentioned, the rearward movement of the breech bolt in Patent No. 1,293,021 is accelerated by the accelerator or lever 8. Also, rearward movement of the barrel extension in said patent is cushioned and limited by a piston supported by a guide F, commonly known as a lock frame. In Patent No. 1,628,226, the accelerator is illustrated, but the rearward movement of the barrel extension is cushioned and limited by an oil buffer, shown in Fig. 27 of said patent.

The parts hereinabove identified in connection with the present drawings and said Patents Nos. 1,293,021 and 1,628,226, have constituted standard equipment on automatic firearms prior to the present invention, and the parts hereinabove identified in connection with the said patents and especially the lock frames and accelerators were especially provided to speed up or increase the rate of firing of the firearms.

According to my present invention, the accelerator is purposely dispensed with and mechanism about to be described especially provided to slow down or retard the rate of firing of the automatic firearm. To this end, in connection with Figs. 1-9 inclusive, I have shown one preferred form of the invention, which I have found in actual practice, materially reduces the rate of firing of automatic firearms of the type mentioned in connection with the above identified patents. Referring to Figs. 1-9 inclusive, the numeral 25 designates generally a lock frame comprising opposite side plates 26 and 27. Arms 28 extend forwardly from the plates 26 and 27 to engage with studs 29 located on opposite sides of the breech bolt lock 30 (similar to that disclosed in said patents) and move said lock 30 downward from the position shown in Fig. 1 wherein the breech bolt is locked to the barrel extension for reciprocable movement therewith. After the lock 30 is moved downward the breech bolt is free to reciprocably move independently of the barrel extension. During the forward movement of the barrel extension from the position shown in Fig. 2, the lock 30 is moved upward and operable during reciprocating movements of the parts by engagement with the cam plate 31 secured to the bottom of the breech casing 11, as disclosed in said foregoing patents, to lock the breech bolt and barrel extension together and maintain them locked when they are established in battery position. A trigger bar 30' is pivotally supported on a pin 31' supported between the plates 26 and 27 with its rear end located for engagement by the trigger 32 to actuate the firing mechanism.

A vertically movable barrel extension retarding member is mounted between the plates or sides 26 and 27 of the lock frame and includes a forwardly projecting arm 33 having on its forward end a hook 34 located at the bottom of the lock frame and in alignment with the barrel extension. The plates 26 and 27 are provided with

vertical grooves 35 and the retarding member has lateral tongues 36 slidably mounted in the grooves 35. At its top the retarding member is provided with a cam formation 39 engageable by a depending portion 40 on the rear end of the breech bolt to depress the retarding member when the breech bolt has nearly completed its course of travel to breech-closing position on counter-recoil movement. It will be noted that the retarding member is located at the forward end of the lock frame while the releasing member 40 on the breech bolt is located at the rear end of the breech bolt so that the breech bolt must travel substantially a distance equal to its entire length before the retarding member which engages with the barrel extension, as presently described, is released. A spring-pressed plunger is located longitudinally in the lock frame between the cam member 39 and the arm 33 of the retarding member. A housing 41 is preferably formed as a part of a spacer block 42 located between and connecting the plates or sides 26 and 27 of the lock frame and through which the pivot 31' of the trigger bar 30' extends. A coil spring 43 is mounted on a rod 44, the rear end of which is 10 slidable in the housing 41. A tube or sleeve 45 surrounds the forward end of the spring and is movable through an opening 46 in the vertically movable barrel extension retarding member. The forward end of the rod 44 is provided with an enlarged head 47 having a slot 48 or other suitable means to facilitate removal of the rod. In the present construction, the head 47 has screw-threaded engagement with the sleeve 45 so that the spring 43 is partly compressed between the housing 41 and the shoulder of the enlarged end 47 of the rod 44. The rear of the barrel extension has a projection 50 aligned with the end 47 of the spring-pressed plunger or rod 44 when the parts are in assembled relation within the breech casing.

My invention provides for any suitable means for effecting movement of the hook 34 upwardly to engage the skirt 51 on the lower portion of the rear end of the barrel extension. It may be seen by reference to Figs. 1-3, that the forward end of the hook 34 on the arm 33 of the retarding member engageable with the barrel extension is provided with a beveled surface 52 on its forward end which serves as a cam for contact by the skirt 51 on the barrel extension to move the retarding member down as the barrel extension moves from the position of Fig. 1 to the position of Fig. 2. In this connection, it is important to provide means for raising the retarding member after the skirt 51 has passed the hook 34 in its rearward travel, and I prefer, though it is not absolutely essential, to use resilient means such as a flat spring 53 in Figs. 1-7 inclusive, or coil springs 54 as shown in Figs. 8 and 9 to exert upward pressure on the arm 33 of the retarding member.

In the embodiment of the invention, shown in Figs. 1-7 inclusive, the flat or leaf spring 53 is relatively wide at its rear end, as indicated by the numeral 56 in Fig. 4 to fit within grooves 57 in the rear portion of the side plates 26 and 27, so that the spring may be readily inserted into the position shown in the drawings with its narrower portion 58 extending forwardly along and beneath the lock frame and with its forward end bearing upwardly against the arm 33 of the retarding member so that the retarding member is normally held in the position of Figs. 2 and 3,

whereby the skirt 51 on the rear of the barrel extension will engage with the beveled surface 52 on the hook 34 and cam the retarding member down when the breech bolt is forced rearwardly in the casing during functioning of the firearm.

An alternative form of means for resiliently forcing the retarding member upwardly is shown in Figs. 8 and 9 wherein the coil springs 54, previously mentioned, are housed in cups 60 slidably mounted in openings 61 in the bottom of a part of the lock frame adjacent the forward end thereof.

I deem it important to provide for centering the means normally urging the retarding member upwardly so as to have even and smooth operation of the gun, that is, to avoid applying pressure on the movable parts at either side of the center in excess of pressure at the other side of the center. Therefore, the flat spring 53 of Figs. 1-7 inclusive, is located with its longitudinal axis substantially in alignment with the longitudinal axis of the arm 33 of the retarding member; and in the construction of Figs. 8 and 9, the coil springs 54 are located at corresponding or equidistant points at opposite sides of the lock frame and retarding member.

Stabilized or guided movement of the spring-pressed plunger or rod 44 is obtained by providing longitudinal grooves 62 in the forward inner surfaces of the side plates 26 and 27 of the lock frame and further providing a plate 63 having lateral ribs or tongues 64 respectively and slidably located in the grooves 62. Preferably, the plate 63 has formed as an integral part thereof the tube 45 which surrounds or houses the forward end of the plunger spring 43.

The lock frame is removably held in the casing by a spring-pressed plunger 65 housed within a tube 66 located between the rear portion of the plates 26 and 27, the projecting end of the plunger 65 being engageable in an opening suitably provided in the side of the breech casing.

To further stabilize the parts of the gun during functioning thereof, especially the lock frame, I have provided on the exterior or outer sides of each of the plates 26 and 27 laterally extending studs 67 and 68 engageable in slots 68' respectively provided therefor in opposite sides of the breech casing, as shown in Figs. 1 and 2. By providing the pairs of studs 67 and 68 in spaced relation to each other on each side of the lock frame, I positively prevent vertical rocking movement of the lock frame during functioning of the gun. Of course, the slots or grooves into which the studs 67-68 fit are proportion to provide a close fit yet permitting easy removal and insertion of the lock frame.

As hereinbefore mentioned, the invention contemplates the provision of two forms of retarding and cushioning means for the breech bolt useable either jointly or separately, and whereas in Figs. 1-9 inclusive, I have shown and described a new form of cushioning and retarding means for barrel extensions; in Figs. 10-12 inclusive I have shown the said retarding means in combination with breech bolt retarding means, the two forms combined on a lock frame. Before proceeding with a detailed description of the structure illustrated in Figs. 10-12, I desire to make it clear that the second form of the invention shown in Figs. 10-12 may be used without the first form of Figs. 1-9 inclusive.

Referring to Figs. 10-12 inclusive, the numeral

25 designates the lock frame, as in Figs. 1-9, and having the oppositely disposed forwardly extending arms 28 which engage the breech bolt lock to unlock the breech bolt and barrel extension upon explosion or firing of each cartridge to permit independent relative movement of the breech bolt and barrel extension to the rear of the breech casing upon recoil. Also, as in Figs. 1-9, the numeral 30' designates the trigger bar pivotally supported on pin 31' mounted between the side plates of the lock frame. Numeral 33 designates the vertically movable hook-like barrel extension retarding member mounted and operable in the same manner as disclosed in Figs. 1-9 inclusive. The member 33 is raised by the spring 53 when the parts are in the position of Fig. 2 so that upon counter-recoil movement of the barrel extension the hook 34 of the hook-like member 33 will engage the skirt 51 depending from the rear of the barrel extension, as shown in Fig. 3. Also, as in Figs. 1-9 inclusive, a housing 41 is formed as a part of the spacer block 42 within which the rear of the rod 44 supporting coil spring 43 is slidably mounted, and the forward end of the rod is provided with enlarged head 47 having screw-threaded engagement in the sleeve 45 into which the forward end of the spring 43 extends to abut at its forward end the enlarged end or head of the rod 44. These parts operate in the same manner as described in connection with Figs. 1-9 inclusive.

While the foregoing arrangement is sufficient to very materially reduce the rate of firing of automatic firearms, the rate of firing may be further reduced or the action of the gun slowed up by providing additional retarding and cushioning means on the lock frame cooperating with the breech bolt during its reciprocating movements upon recoil and counter-recoil. To this end, as shown in Figs. 10-12 inclusive, I provide a hook or pawl 70 suitably pivoted on a shoulder screw 71 which threads into a shoe 72 and having its head 73 disposed in slot 74 in the right side of the lock frame for sliding movement therein, as presently described in detail. The shoe 72 has side walls 75 and a rear wall or inner wall 76 into which latter wall the screw 71 is threaded, as shown in Fig. 10. A coil spring 77 is compressed between the lower side wall of the shoe and the hook 70 tending to normally urge or retain the hook in raised position for engagement with the depending portion 40 at the rear of the breech bolt when the breech bolt is in its rearmost position. The front of the hook 70 has a beveled surface 78 which is engaged by the beveled surface 79 of the breech bolt as it moves rearward upon recoil to cam the hook down against the action of the spring 77. As the breech bolt returns forward upon counter-recoil the hook engages the flange 40 on the breech bolt to retard its forward movement. The retarding mechanism includes a retarder device, now to be described comprising a bracket 80 which is rigidly secured to the lock frame adjacent the bottom thereof and preferably against the spacer 42 and is provided with a bore 81 within which a rod 82 is slidably mounted for reciprocating movement. A coil spring 83 is compressed between the bracket 80 and the end of a rack 84 formed as a part of or rigidly connected to the rod 82. The upper or rear end 85 of the rack 84 is reduced and mounted in an opening in the forward end of the shoe 72 and preferably rigidly connected therein by any suitable means. A pinion 86 is pivoted to the right side of the lock frame as indicated at

87 and has two sets of teeth, a relatively small peripheral group 88 which mesh with the teeth 89 on the rack 84 and a larger group of teeth 89' which cooperate with a rocking pawl 90 pivoted to the left side of the lock frame adjacent the bottom thereof at 91. The rocking pawl has claws or teeth 92 which alternately engage the larger teeth on the pinion.

In operation, the structure of Fig. 11 functions as follows: as the breech bolt returns from its rearmost recoil position toward breech-closing or firing position, the pressure of the driving or counter-recoil spring which bears against the back plate and the breech bolt causes the depending portion 40 of the breech bolt to move toward the hook 70. The screw 73 on which the rear end of the hook 70 is mounted moves downwardly and forwardly in the inclined slot 74 under the pressure exerted on the hook 70 by the depending portion 40 of the breech bolt under the force of the driving or recoil spring, and consequently the hook 70 is moved in similar manner until it has been disengaged from the depending portion 40 of the breech bolt. The shoe 72 also has movement in a direction extending forwardly and downwardly causing the rack 84 to be moved against the spring 83 partly compressing the spring. The extension 82 of the rack has guided movement in the bore 81 of the bracket 80 during the foregoing movements of the parts. The downward and forward movement of the rack effects rotation of the pinion 86 by engagement of the teeth 88 of the pinion with the teeth 89 of the rack, and the rotation of the pinion causes alternate engagement of the claws on teeth 92 on the rocking pawl 90 with the teeth 89' on the pinion. Thus, the counter-recoil movement of the breech bolt is retarded by the rack and pinion or escapement mechanism above described and the operation of the hook and shoe. The compression of the spring 83 is gradual so that the movements of the rack and pinion and rocking pawl must also be gradual whereby the hook is not suddenly released from engagement with the breech bolt and the breech bolt is released only at a predetermined time.

As has been previously explained in connection with Figs. 1-9 inclusive, the hook 34 on the barrel extension retarding member 33 by engagement with the depending portion 51 on the rear of the barrel extension delays return of the parts to battery position. Thus by delaying the breech bolt by the hook 70 before it can begin its forward travel to engage the cam formation 39 on top of the barrel extension retarding member, the action or rate of firing of the gun is reduced.

As soon as the depending portion 40 on the rear of the breech bolt has passed, in its counter-recoil movement, the hook 70 in its completely depressed position, the hook together with the shoe, rack, pinion and rocking pawl, are returned to the position shown in Fig. 11 with the hook 70 disposed in the path of movement of the beveled surface 79 on the rear of the depending portion 40 of the breech bolt so that upon recoil the breech bolt will be again retarded or detained upon counter-recoil movement by engagement of the hook therewith, as shown in Fig. 11, and this operation is continuous so long as the firing of cartridges is continued.

Also, as previously pointed out, both of the retarding mechanisms may be used conjointly, as shown in Fig. 11, or may be used independently according to the rate of firing desired to be had.

What I claim is:

1. An automatic firearm comprising in operative relationship a breech casing, a breech bolt mounted within said casing for automatic movement longitudinally thereof between firing and recoil positions in accordance with the functioning of the firearm, said breech bolt having adjacent its rearward end a projection depending from its underside, biasing means normally urging said breech bolt toward firing position, and a lock frame mounted within said breech casing adjacent its rearward end, said lock frame being below said breech bolt, in combination with a retarder device mounted within said lock frame, and means for connecting said retarder device with said breech bolt, said connecting means being mounted substantially entirely within said lock frame and reciprocably movable in a path extending forward and downward in said lock frame and including a member normally projecting above said lock frame in position to engage said projection depending from said breech bolt during a portion of the movement of said breech bolt toward firing position, whereby said member connects said breech bolt to said retarder device during said portion of the movement of said breech bolt and the force of said retarder device opposes the force of said biasing means and causes a delay in the return of the breech bolt to firing position until said member moves downward in said lock frame sufficiently to disengage said projection on said breech bolt.

2. An automatic firearm comprising in operative relationship a breech casing, a breech bolt

mounted within said casing for automatic movement longitudinally thereof between firing and recoil positions in accordance with the functioning of the firearm, said breech bolt having adjacent its rearward end a projection depending from its underside, biasing means normally urging said breech bolt toward firing position, and a lock frame mounted within said breech casing adjacent its rearward end, said lock frame being below said breech bolt, in combination with a retarder device mounted within said lock frame and comprising an escapement mechanism and operating pinion, and means for connecting said retarder device with said breech bolt, said connecting means being mounted substantially entirely within said lock frame and reciprocably movable in a path extending forward and downward in said lock frame and including a rack engageable with said pinion and a member normally projecting above said lock frame in position to engage said projection depending from said breech bolt during a portion of the movement of said breech bolt toward firing position, whereby said member connects said breech bolt to said escapement mechanism during said portion of the movement of said breech bolt and said escapement mechanism opposes the force of said biasing means and causes a delay in the return of the breech bolt to firing position until said member moves downward in said lock frame sufficiently to disengage said projection on said breech bolt.

GEORGE IRONSIDE.
